UNITED STATES PATENT OFFICE.

WILLIAM HENRY WAY, OF OSSINING, NEW YORK

ICE-CUTTING MACHINE.

Application filed May 23, 1923. Serial No. 640,866.

This invention relates to ice cutting machines and has for an object to provide an improved machine in which the saw is power driven; which is power propelled; which is self guiding in cutting strips of ice of various desired and variable widths; which will cut a slot in the surface of the ice to variable depths; with which the saw can be shifted into and out of engagement with the ice in a simple manner and with a minimum of manual effort; which is relatively compact, light in weight, simple and inexpensive in construction, and rapid and efficient in use. Other objects and advantages will be apparent from the following description of an embodiment of the invention and the novel features will be particularly pointed out hereinafter in claims.

In the accompanying drawing,

20 Fig. 1 is a side elevation of a machine constructed in accordance with the invention. Fig. 2 is a plan of the same. Fig. 3 is an end elevation of the same, and Fig. 4 is an elevation of a portion of the 25 same for showing the latch device.

Figure 5 is a detail sectional view of the differential device.

Figure 6 is a top edge view of one of the 30 guide plates.

In the illustrated embodiment of the invention, the running gear is in the nature of a sled having runners and connected near the ends by cross rods 2 and 3. Pivot stud shafts 4 are provided upon the outer faces 35 of the runners and extend horizontally in alignment with one another. A frame 5 is mounted upon the pivot studs for oscillation about the axis thereof. A shaft 6 extends horizontally across the frame, and is rotatably mounted in bearing blocks 7, provided 40 upon one end of the frame. A saw 8 is carried by the shaft for rotation therewith and in a substantially vertical plane. A suitable driving motor 9, such as an internal combustion engine, is mounted in the frame 45 to extend from the other end thereof in a direction lengthwise of the frame. A pair of aligned shafts 10 extend transversely of the frame and are connected through a suitable differential 50 with the main driving shaft of the engine. One well known form of such a differential that may be employed is clearly shown in sectional detail in Figure 5, where the main driving shaft carries 55 a cone pinion that meshes with a large bevel gear that carries a series of four cone pinions

that engage the two bevel gears, one on each shaft 10, as is usual in well known forms of differential gearing in automobile practice. A sprocket wheel 12 is fixed upon the outer 60 end of each of the shafts. Sprocket pinions 13 are fixed upon the outer ends of the shaft 6, and chains 14 connect these pinions with the driving sprocket wheels 12. The power of the engine may be delivered to the main 65 driving shaft through a suitable clutch and transmission mechanism 15 which is similar to, and controlled in the same manner as, the corresponding parts of an automobile. A radiator 16 is provided upon the frame, at 70 the end opposite from the saw, and connected to the engine to cool it in the same manner as in an automobile. The fuel tank 17 is mounted transversely of the frame and connected to the engine through a suitable carburetor in a manner well known in the art. The quantity of fuel mixture admitted to the engine is controlled in a manner similar to that employed in automobiles, the necessary manipulation being made through 75 a Bowden wire mechanism 18 and a suitable operating lever 19. The lever 19 is mounted on one of the handles 20 that are provided upon the frame at the end opposite from the saw for enabling the shifting of the 80 machine into cutting position and for drawing the sled over the ice. The ignition mechanism 21 is mounted on the frame in any suitable manner and place, such as above the engine, and may be controlled from a suitable switch device 22 provided upon one 85 of the handles 20. A crank handle 23 is provided at the handle end of the frame, by means of which the engine is turned over in starting.

The cross rod 2 at the forward or handle end of the sled, is extended laterally on each side of the sled, and on each extension carries an arm 24 with a guide plate 25 extending laterally from the free end thereof. When the arm is vertical the plate will be above the surface of the ice, and when horizontal the plate will depend below the surface of the ice. When the plate is placed in a previously sawed slot, it will guide the sled in a direction at a uniform distance from the guiding slot so that the slot being cut in the ice will be everywhere the same distance from the guiding slot. The arms 24 are rotatably and slidably adjustable on the rod extensions so as to be set for cutting strips of different widths. When the arms 90

are placed in a vertical position the guide plates will be ineffective. The arms are attached to the extensions by clamping means so that they may be secured in their different 5 adjusted positions.

The arms 24 are separably attached to the rod 2 so that either guide blade 25 may be introduced into the previously made saw kerf as required, which guide plate by action 10 of gravity is held within the kerf for guiding the machine. Thus should an obstacle be encountered in the guiding slot the forward engaging corner of the plate 25 being rounded, as shown at 25^a, the blade will 15 easily be lifted sufficiently to pass over the impediment and thereafter resume its normal operative position in the groove.

In order to facilitate the passage of the guiding plate 25 over obstructions and reduce to a minimum the ill effects thereof, the 20 plates are themselves rotatably mounted upon the arms 24 and held in operable position thereon by means of a spring 25^c to each plate, having one end thereof secured to the 25 hub of the arm by means of the pin 24^a, its opposite end being attached to the plate 25 by the pin 25^b. A stop pin 25^d suitably projecting from the inner face of the plate engages the arm 24 so as to be held by action 30 of the spring at substantially right angles to the longitudinal axis of the arm upon which it is supported. The forward engaging corner of the guide blade 25 is rounded as shown at 25^a in Fig. 1 to permit the member to slide over any obstacle encountered in the groove instead of plowing through such resisting and disturbing elements.

The frame is not entirely balanced about the axis of oscillation, but has a small preponderance of weight on the saw carrying end, so that when free the frame will, by its own weight (including the weight of the parts carried thereby), tilt in a direction to carry the saw into engagement with the ice. 40 A plate 26 is coupled to the frame at the saw end by a bolt 27 passing through the frame and through one of the apertures 28 of the plate 26, so as to depend from the frame and, by its engagement with the 45 surface of the ice, limit the tilting of the frame and thereby serve as a depth gauge for the saw. The gauge is variable by passing the bolt 27 through any one of the apertures 28 of the plate. A suitable guard 29 is supported by bars 30 upon the frame and over the saw, so as to prevent anyone from injury by falling upon the saw.

A latch 31 is pivoted upon the handle end of the frame so as to be movable into locking 60 engagement with a pin 32 provided upon one of the runners of the sled when the frame is tilted in a direction to carry the saw entirely above the surface of the ice. The latch 31 may be operated into or out of engagement with the pin by suitable link

mechanism 33 that extends into a readily accessible part on the machine near the handles. The rotary saw is driven in a direction to carry its teeth downwardly into sawing engagement with the ice, with the result 70 that the saw teeth will have horizontal traction upon the ice being cut sufficiently to propel the machine over the ice so easily that but little propelling force is necessary, and the traction of the saw teeth on the ice has been found to be ample to propel the sled. Because the axis of rotation of the saw is above the ice, the teeth in sawing engagement with the ice will have a considerable horizontal component of travel which 75 provides the horizontal traction.

In operation, let it be assumed that the frame is latched to the sled with the saw entirely above the surface of the ice. The sled is pushed or drawn into position with the saw above the ice where a slot is to be cut. The engine is then started and the clutch operated to cause the engine to drive the saw at a rapid rate. The link mechanism 33 is then operated to unlatch the frame from the sled, and the frame is allowed to tilt by gravity in a direction to carry the rotating saw into engagement with the ice. The engagement of the plate 26 with the surface of the ice limits the tilting 95 of the frame and thereby the depth to which the saw will cut. The plate may be adjusted vertically to vary the depth of the cut. The sled, by the traction of the saw upon the ice, is propelled over the ice in the direction in which the cut is being made, the handle end of the frame being the forward end relatively to the direction of travel, and the saw while being moved with the sled will cut a slot in the ice. After one slot has 100 been cut, the sled is placed adjacent and parallel with the slot, with the saw spaced laterally from this slot a distance equal to the desired width of the strip to be cut. One of the arms 24 is then shifted to carry 105 its plate 25 into the previously cut slot so as to guide the sled in a direction parallel with the previously cut slot. The sled is again propelled over the ice, with the handle end of the frame foremost in the direction of travel, so as to cut a second slot equi-distant at all points from the first slot. When shifting the sled from one position to another the frame is always tilted to remove the saw from the ice and hold it removed while the shifting is taking place. If desired the latch 31 can be used to hold 115 the frame in the tilted position with the saw elevated. The fuel spark and other controlling devices for the engine are all conveniently accessible on the frame, and the cutting operation will be very rapid.

It will be obvious that various changes in the details and arrangements of parts herein described and illustrated for the purpose 120

of explaining the nature of the invention may be made by those skilled in the art within the principle and scope of the invention.

5 I claim:

1. In an ice cutting machine comprising a running gear movable over the ice to be cut and a tiltable frame thereon, a saw carried by the frame for rotation in a vertical plane 10 at one end of the tiltable frame; a driving motor mounted on the frame, and means including a differential device carried by the frame, driven by the motor and connected to the opposite sides of the saw to drive 15 the same.
2. In an ice cutting machine comprising a running gear movable over the ice to be cut and a frame operably mounted thereon, a circular saw mounted centrally upon a 20 mandrel rotatably supported on said frame; a driving motor; a differential device operated by the motor and having a pair of aligned shafts extending transversely of the frame; sprocket pinions on said aligned 25 shafts; sprockets on said mandrel correspondingly aligned with said pinions; and

transmission means connecting each of said pinions with a sprocket.

3. In an ice cutting machine, the combination of a sled member and a frame operably mounted thereon, cutting means thereon, and guiding means on said sled member, consisting of a reversible guide plate held rigidly against lateral movement, the forward corner thereof being rounded to ride over obstructions, an arm member mounted on the sled member, on which arm member the guide plate is movably carried, and yielding means affixed to the guide plate and the arm member. 30 35 40

4. In an ice cutting machine, the combination of a sled member having runners, a frame thereon, a circular cutting saw, a driving motor for said saw, and guiding means, comprising a vertical plate, an arm 45 mounted on the runner to which arm the plate is pivoted, a stop device on the plate, and a spring attached to the plate and to the arm.

In testimony whereof I have hereunto set 50 my hand.

WILLIAM HENRY WAY.
